UNITED STATES PATENT OFFICE.

GROVER L. LESLIE, OF ATLANTA, GEORGIA.

DESIGN FOR A COAT AND HAT RACK.

44,373.

Specification for Design.

Patented July 22, 1913.

Application filed April 21, 1913. Serial No. 762,734. Term of patent 14 years.

To all whom it may concern:

Be it known that I, GROVER L. LESLIE, a citizen of the United States, residing at Atlanta, in the county of Fulton and State of Georgia, have invented a new, original, and ornamental Design for Coat and Hat Racks, of which the following is a specification, reference being had to the accompanying drawing, forming part thereof.

Figure 1 is a front elevation of a coat and

hat rack showing my new design. Fig. 2 is an end view.

I claim:

The ornamental design for a coat and hat rack as shown.

GROVER L. LESLIE.
